UNITED STATES PATENT OFFICE

2,509,300

LINT TRAP

Kenneth E. Hendrickson, Sioux City, Iowa

Application April 5, 1948, Serial No. 19,002

1 Claim. (Cl. 183—52)

1

This invention relates to new and useful improvements in lint traps and the primary object of the present invention is to provide a novel and improved attachment for tumbling machines and more particularly those machines employed in laundry plants, dry cleaning plants and dyeing plants for drying and deodorizing clothes, that are so designed as to remove lint from the exhausted air leaving the tumbling machine.

Another important object of the present invention is to provide a lint trap applicable for attachment to a tumbling machine for clothing and embodies a novel and improved filter screen that is manually agitated in a convenient manner to effect a removal of the lint therefrom whereby the lint will descend into a lint chamber which is quickly and readily accessible for cleaning.

A further object of the present invention is to provide a lint trap that is applied to the exhaust pipe of a tumbler or tumbling machine for clothing and the like and which is disposed in the same room with the tumbling machine so that the said trap can be cleaned quickly during the emptying and refilling operation of the tumbling machine, without the necessity of having to shut down the tumbling machine and without the necessity of having to employ special tools or skilled labor.

A still further aim of the present invention is to provide a lint trap that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the lint trap constructed in accordance with the present invention, and showing the same removed from a tumbling machine, and with parts of the intake pipe and outlet pipe thereof broken away and shown in section;

Figure 2 is a longitudinal vertical sectional view taken substantially on the plane of section line 2—2 of Figure 1;

Figure 3 is a longitudinal horizontal sectional view taken substantially on the plane of section line 3—3 of Figure 2;

Figure 4 is a transverse vertical sectional view taken substantially on the plane of section line

2

4—4 of Figure 2, and with parts removed therefrom; and,

Figure 5 is a fragmentary transverse sectional view taken substantially on the plane of section line 5—5 of Figure 1, and showing the locking device that is employed in conjunction with the present invention.

Referring now to the drawings in detail, wherein for the purpose of illustration, there is disclosed a preferred embodiment of the present invention, the numeral 10 represents a substantially rectangular casing or housing of any suitable material generally, that includes a bottom wall 12, an upper wall 14, a forward wall or end wall 16, a rear wall or end wall 18, and a pair of side walls 20 and 22. One of the side walls, for example side wall 20, is formed with a longitudinal opening 24 in its lower portion and receives a door or panel 26 that is hinged as at 28 to the side wall 20.

The hinged panel 26 supports a rotatable bar or pin 30 the inner end of which is provided with a fixed locking lip or lug 32 that engages the inner face of an upstanding lug 34 that is rigidly secured to the bottom wall 12 for normally holding the panel 26 in a closed and locked position. A finger grip 36 is secured to the outer end of the bar 30 for rotating the same into and out of a locked position with the lug 34.

The forward wall 16 of the casing 10 is provided with an entrance opening 38 in the upper portion thereof that is disposed centrally within a collar or sleeve 40 that projects outwardly or forwardly from the forward wall 16 and which 35 engages the inner surface of an exhaust or intake pipe 42.

Projecting upwardly from the upper wall 14 of the casing 10, is an annular sleeve 44 that engages an outlet pipe 46. The upper wall 14 is provided with an exit opening 48 that communicates with the sleeve 44.

Fixed to the inner surface of the forward wall 16 and below the entrance opening 38, is the flanged end portion 50 of a substantially horizontal, lower baffle plate 52 the free rear end of which terminates in spaced relationship from the rear wall 18 and is turned upwardly to provide a substantially vertical section 54 that opposes a portion of the entrance opening 38.

The numeral 56 represents a downwardly and rearwardly inclined upper baffle and support plate that opposes the exit opening 48. One end 58 of this plate 56 is fixed to the upper wall 14 of the casing 10 between the exit opening 48 and the forward wall 16, and the remaining and lower end

60 of this plate 56 terminates above and rearwardly from the vertical section 54 of the lower baffle plate 52 to provide a transverse opening 62.

Hinged to the rear wall 18 of the casing 10, is the upper edge 64 of a rear baffle plate 66 that supports pivotal holding bars 68 the free ends of which terminate in bearing fingers 70 for engaging strips or lugs 72 fixed to the inner surface of the rear wall 18, to normally hold the baffle plate 66 in a forwardly and downwardly inclined position as shown in Figure 2, opposing the transverse opening 62 between the baffles 52 and 56. When the bearing fingers 70 are disengaged with the strips 72, the baffle plate 66 will drop to the dotted line position shown in Figure 2.

Extending transversely between the side walls 20 and 22 of the casing 10, is a pivot shaft 74 that is spaced slightly adjacent and above the lower edge 60 of the upper baffle plate 56. This pivot shaft 74 is fixed to one edge of a substantially rectangular filter unit or screen 76 the upper edge or free edge 78 of which is normally engaged with the inner face of the upper wall 14, to retain the filter unit spaced parallel to the baffle plate 66.

It should be noted, that when the baffle plate 66 is raised in its normal position or inclined position, the upper edge 64 thereof will engage the upper edge 78 of the filter screen 76 to limit the downward pivotal movement of the latter, however, when the baffle plate is lowered or when the same is in the dotted line position as shown in Figure 2, the filter screen 76 may be easily pivoted to a vertical position illustrated by dotted lines in Figure 2.

Integrally formed with the pivot shaft 74 at one end thereof, is a lever or handle 80 that is spaced parallel to one side of the casing, preferably side wall 20. When the lever 80 is raised and lowered, the filter screen 76 will be agitated sufficiently to remove lint therefrom, whereby the lint will drop into a lint chamber 82 disposed within the casing 10 below the baffle plate 52.

In practical use of the present invention, the inlet pipe 42 is applied to the exhaust pipe of a suitable tumbling machine (not shown) so that the air exhausted from the tumbling machine will pass into the casing 10. The air directed into the casing 10 will pass between the baffle plates 52 and 56 through the opening 62 engage the inclined rear baffle plate 66 and will be directed through the filter screen 76 and hence outwardly through the exit opening 48. As the lint carried by the air engages the filter screen 76 the same will be retained thereon whereby the air leaving the casing 10 will be filtered and free from lint.

To remove the lint from the screen 76, it is merely necessary to actuate the lever 80 in a raising and lowering motion which will cause the lint carried by the screen 76 to drop therefrom into the chamber 82. The chamber 82 is easily accessible by raising the hinged panel 26 so that the present casing 10 and parts thereof may be quickly and readily cleaned for continuous use.

In view of the foregoing description taken in conjunction with the accompanying drawings it is believed that a clear understanding of the device will be quite apparent to those skilled in this art. A more detailed description is accordingly deemed unnecessary.

15 It is to be understood, however, that even though there is herein shown and described a preferred embodiment of the invention the same is susceptible to certain changes fully comprehended by the spirit of the invention as herein described and the scope of the appended claim.

20 Having described the invention, what is claimed as new is:

25 A lint trap comprising a casing including a forward wall, an upper wall and a hinged side wall; means for normally locking the hinged side wall in a closed position, said forward wall having an entrance opening therein, said upper wall having an exit opening therein, a pair of baffles mounted in the casing and arranged to provide a 30 restricted opening for air entering the casing from the entrance opening, a filter screen pivoted within the casing adjacent the exit opening, means for agitating the filter to remove lint therefrom, means provided in the casing for receiving lint removed from the filter during agitation thereof, and an inclined baffle hingedly mounted within the casing having an upper edge for normally limiting the pivotal movement of the filter in one direction, and means normally 35 retaining the hinged baffle in an inclined position and spaced parallel to the filter.
